UNITED STATES PATENT OFFICE

JOHN E. MUHLEFELD, OF SCARSDALE, NEW YORK

LOCOMOTIVE TENDER

Application filed January 21, 1929. Serial No. 372,560.

This invention relates to locomotive tenders, and has for its primary object and purpose to provide a tender particularly designed for use in connection with freight locomotives having provision for the comfortable housing and protection of the conductor or brakeman and means whereby easy and quick communication may be had when necessary, with the engineer.

10 More particularly, my present invention contemplates the provision on a rear extension of the tender under frame of a more or less commodious cabin in which the conductor or brakeman may be stationed and 15 provided with a telephone or speaking tube connection with the engineer's cabin so that when it is necessary for the engineer and conductor to consult each other, the conductor need not enter the engineer's cabin, and is 20 also protected against possible serious injury in the event of derailment of the locomotive, boiler explosion, or other accident.

It is a further general object of the invention to provide an improved locomotive tender as above characterized which does not necessitate material alteration in the present standard construction, or necessitate a decrease in the water and coal, oil or other fuel carrying capacity of the locomotive tender.

30 With the above and other objects in view, the invention consists in the improved locomotive tender, and in the form, construction and relative arrangement of its several parts, as will be hereinafter more fully described, 35 illustrated in the accompanying drawings, and subsequently incorporated in the subjoined claims.

In the drawings, wherein I have shown one simple and satisfactory embodiment of the 40 invention, and in which similar reference characters designate corresponding parts throughout the several views,

Figure 1 is a side elevation of a locomotive tender provided with my present improvements;

Fig. 2 is a top plan view thereof, and

Fig. 3 is an end elevation.

In modern railway transportation systems, 50 large high-powered freight locomotives are used for hauling freight trains which are

composed of from 100 to 150 individual cars and measuring in total length from 4500 to 5700 feet.

It has heretofore been customary in the operation of such freight trains for the conductor and head brakeman to be stationed in the caboose at the rear end of the train. 55 When the train arrives at points where train orders are received, it becomes necessary for the conductor and engineer to directly communicate with each other and the former must therefore, walk the entire length of the train from the caboose to the engine cab. This consumes a great deal of time with consequent delay in the movement of the train. 60 Also, many other cases arise where the conductor must leave the caboose and communicate with the engineer or to pick up or set out freight cars, and for other reasons.

It is the primary purpose of my present improvements to provide an engine tender construction which will eliminate delays incident to the above cause and at the same time obviate the necessity of the conductor entering the engineer's cabin on the locomotive. 70 To this end, as shown in the drawings, the conventional type of tender which I have selected for purposes of illustration, is provided with a water carrying compartment indicated at 5, a compartment 6 for coal, lignite or other solid carbonaceous fuel, and a compartment 7 for fuel oil. The under frame 8 of the tender is extended rearwardly beyond the water compartment 5 as shown at 9, and upon this rear extension of the tender under frame, a cabin or auxiliary caboose 10 is constructed. As herein shown, this cabin is provided in one side wall thereof with an entrance door 11 and above the water compartment 5, the cabin is of reduced width, or is set back at this side of the tender as indicated at 12 so that the trainmen may ascend a ladder indicated at A and walk over the top of the tender when it is necessary to communicate with the engine crew.

Within the cabin 12, a speaking tube or telephone connection indicated at 13 is installed which affords ready communication between the occupant of the cabin and the engineer. Additional facilities are also pro- 100

vided within the cabin for the purpose of making out reports and other clerical work which may be required of the conductor enroute.

From the above, it will be seen that by providing the cabin at the rear end of the tender for the conductor, he may at all times get into instant communication with the locomotive engineer for the purpose of consultation as to train stops for the purpose of taking on water, and to consider such train orders as may be received. It is of course, understood that the rear end of the train will be protected by a brakeman or flagman who remains at all times in the caboose at the rear end of the train. By locating the locomotive engineer and conductor close together, it will be apparent that delays in the train movement incident to the necessity of the conductor walking from the caboose at the rear end of the train to the engineer's cabin and then returning to the caboose, are entirely eliminated, so that by means of my improvements, the transportation of freight may be materially expedited. A further advantage resides in the fact that since the conductor need not at any time enter the cabin of the locomotive, in the event of a boiler explosion or other accident such as a broken draw bar, side rod or crank pin, a broken or loose driving wheel tire or derailment of the locomotive, liability of the conductor, head brakeman, or other persons being killed or seriously injured, is greatly reduced.

From the foregoing description considered in connection with the accompanying drawing, the nature of my present invention and its several advantages in practical use will be readily understood. While I have shown a particular type of locomotive tender and a desirable form and construction of the cabin which is erected on the rear extension of the tender under frame, it is to be understood that the invention is applicable to various other standard forms of tenders and that the auxiliary cabin or caboose may also be considerably modified in the details of its construction. By the provision of such a separate compartment for the head brakeman and conductor of the train, the engineer is never disturbed by the presence of members of the train crew in his cabin, and possibility of erroneous interpretation of signals given either by the hand or by a lantern, is greatly reduced. It will further be apparent that the incorporation of my present improvements will not materially add to the manufacturing cost of such locomotive tenders.

While I have herein disclosed a practical embodiment of the invention, it is nevertheless to be understood that the same might be incorporated in various other structural forms, and I accordingly reserve the privilege of resorting to all such legitimate

changes as may be fairly embodied within the spirit and scope of the invention as claimed.

I claim:

1. A tender for locomotives comprising an extended under frame, a tender body supported upon said extended under frame, and a cabin at the rear end of the tender body affording a compartment for housing members of the train crew. 70

2. A locomotive tender comprising an under frame, a tender body supported on the under frame, said under frame having a rear end extension projecting beyond the tender body, and a cabin supported on said under frame extension providing a compartment for housing members of the train crew. 75

3. A locomotive tender comprising an under frame, a tender body supported on the under frame, said under frame having a rear end extension projecting beyond the tender body, a cabin supported on said under frame extension providing a compartment for housing members of the train crew, and means between the tender cabin and the engine cab affording verbal communication between the occupant thereof and the engine crew. 80

4. A locomotive tender comprising an under frame, a tender body supported on the under frame, said under frame having a rear end extension projecting beyond the tender body, a cabin supported on said under frame extension providing a compartment for housing members of the train crew, and a telephone or speaking tube installed in the cabin connected with the engineer's cabin. 85

5. A locomotive tender comprising an under frame, a tender body supported on said under frame having water and fuel compartments, said under frame having a rear end extension projecting beyond the tender body, a cabin supported on said under frame extension providing a compartment for members of the train crew, said compartment projecting vertically above the tender body and being cut away at one side thereof to provide a walk, a ladder mounted on the rear side of the cabin leading to said walk, and a telephone or speaking tube installed in said compartment and connected with the engineer's cabin. 90

In testimony that I claim the foregoing as my invention, I have signed my name hereto.

JOHN E. MUHLFELD.
